D. W. BAKER.

VEST.

No. 391,768.

Patented Oct. 23, 1888.

FIG. 1.

NITNESSES. FIG. 2.

H. W. Baker.
C. F. Codget.

INVENTOR.
Daniel W. Baker.
By H. C. Schenck, Atty.

UNITED STATES PATENT OFFICE.

DANIEL W. BAKER, OF BOSTON, MASSACHUSETTS.

VEST.

SPECIFICATION forming part of Letters Patent No. 391,768, dated October 23, 1888.

Application filed May 12, 1888. Serial No. 273,697. (No model.)

To all whom it may concern:

Be it known that I, DANIEL W. BAKER, a citizen of the United States, residing at Boston, in the county of Suffolk and State of Massachusetts, have invented certain new and useful Improvements in Vests, of which the following is a full, clear, and exact description, reference being had to the accompanying drawings, making part of this specification, in which—

Figure 1 is an elevation of a vest-spring constructed in accordance with my invention. Fig. 2 is a view representing one of my springs applied to the inner side of the front of a vest. Fig. 3 is a view of the outside of the front of a vest and the upper portion of a pair of trousers, showing in dotted lines the spring attached to the inner side of the vest, and illustrating the manner in which it is connected, when in use, with the upper portion of the trousers.

My invention has for its object to prevent the lower portion of the front of a vest from rising up and getting out of shape, as now frequently occurs; and to this end my invention consists in the improved vest which I shall hereinafter fully describe and claim.

In the said drawings, A represents a portion of the front of a vest, to the lower part of the inner side of which is secured a spring, B, composed of a single piece of wire bent into the form shown, and having two diverging arms, *a*, *b*, a coil, *c*, being preferably formed at the junction of these arms to render the spring more elastic. The lower arm, *a*, of the spring extends along near the lower edge of the vest-front, as seen in Figs. 2 and 3, and is provided at its outer end with a loop or eye, *d*, which is securely sewed or otherwise fastened to the vest-lining, as seen in Fig. 2. The end of the arm *a* may, however, be provided with any other suitable means for attaching it to the inner side of the vest, and this arm *a* may be covered with a piece of tape or narrow strip of cloth, *e*, as seen in Fig. 2, or left exposed, as preferred. The spring B is further secured to the vest and kept in place by a piece of tape, *f*, sewed over the coil *c*. The

upper arm, *b*, of the spring is not attached to the vest-lining and is free to be bent downwardly toward the fixed arm *a*, and when so bent down its outer end is caught onto or connected with the upper portion of the trousers D, as seen in Fig. 3, when the tendency of the two arms *a*, *b* to spring apart will cause the lower arm, *a*, to exert a pressure away from the upper arm, *b*, and force down the lower portion of the vest-front, to which, as before stated, the said arm *a* is attached, whereby the vest is held down with a spring-pressure which will readily yield to the movements of the body, and yet keep the vest smooth and in its proper position and prevent it from rising up and getting out of shape, desiderata hitherto unattained.

The outer end of the free arm *b* of the spring B is bent to form a hook, *g*, which, when the arm *b* is bent down, after putting on the vest, is adapted to catch under the neck of one of the buttons or other fastening of the front opening or "fly" of the trousers; but the outer end of the arm *b* may be otherwise suitably shaped or provided with any suitable means to enable it to engage or be connected with the front portion of the trousers, and be easily disconnected therefrom when the vest is to be taken off.

What I claim as my invention, and desire to secure by Letters Patent, is—

As a new article of manufacture, a vest having the inner side of its front portion provided with a spring formed of a single piece of wire, one end of which is secured to the vest, while the opposite end is free and provided with a bent or hook-shaped end, whereby it may engage with the neck of a button or other fastening on the upper portion of the trousers to hold the vest down, substantially as herein described.

Witness my hand this 9th day of May, A. D. 1888.

DANIEL W. BAKER.

In presence of—

P. E. TESCHEMACHER,
HARRY W. AIKEN.
